UNITED STATES PATENT OFFICE.

HERMAN W. UHLENKOTT, OF FERDINAND, IDAHO.

SAW-SET.

1,094,497.

Specification of Letters Patent. Patented Apr. 28, 1914.

Application filed April 22, 1913. Serial No. 762,921.

To all whom it may concern:

Be it known that I, HERMAN W. UHLENKOTT, a citizen of the United States, residing at Ferdinand, in the county of Idaho, 5 State of Idaho, have invented certain new and useful Improvements in Saw-Sets; and I do hereby declare the following to be a full, clear, and exact description of the invention, such as will enable others skilled 10 in the art to which it appertains to make and use the same.

The present invention is directed to improvements in saw sets, and has for its object to provide a device of this character 15 with interchangeable tooth engaging heads, so that saw teeth of various sizes can be set.

A further object of the invention is to provide a device of this character which is exceedingly simple in construction, and one 20 which can be manipulated to quickly set the teeth of saws at proper angles to the body thereof.

With these and other objects in view, this invention resides in the novel features of 25 construction, formation, combination and arrangement of parts to be hereinafter more fully described, claimed and illustrated in the accompanying drawing in which:—

30 Figure 1 is a side elevation of the device, showing it in use in connection with a saw. Fig. 2 is a longitudinal sectional view through the same. Fig. 3 is a sectional view taken at right angles to the sectional view of Fig. 2. Fig. 4 is a detail perspective view of one of the tooth engaging heads.

Referring to the drawing, the numeral 1 35 designates the handle, which is rectangular in cross section, and is slidably engaged by the slot 2 formed in the block 3, said block terminating at one end in a curved arm 4. Passing through one end of the block 3 is a set screw 5, the inner end of which being 40 adapted to engage one edge of the handle to hold the block 3 and arm 4 in adjusted positions upon said handle. Formed in one end of the handle is a longitudinal bore 6, which opens into the open recess 7 45 formed in said handle, and in which oper-

ates the milled nut 8, said nut being adapted to engage the threaded end of the shank 9, which is passed through the bore 6, and as the head 10 is formed integral with the shank, the same will be held against accidental displacement. The head 10 is provided at one end with a tooth engaging slot 11, which leads to the transverse opening 12, said opening serving to accommodate the point of the engaged tooth to prevent 60 injury thereto. One end of the bore 6 opens into the groove 13 formed upon the inner end of the handle and is engaged by the convexed edge 14 formed upon the head 10. Thus it will be seen that when the head 10 65 engages the groove 13, and the nut 8 is manipulated, that accidental rotation of the head is prevented.

In operation the slot 11 is engaged with the tooth to be set, and at which time the 70 arm 4 has its end engaged against the body of the saw, it being of course understood that the handle has been operated to set the tooth, and that the angle of the same is limited when the arm contacts with the saw 75 body.

Further it will be noted that by providing interchangeable heads, that not only saws of different sizes can be set, but that saws of different styles can be operated 80 upon.

What is claimed is:—

A saw set comprising a handle, said handle having one end provided with a longitudinal bore which opens into a recess, a nut 85 mounted in the recess, a head having a tooth engaging slot carried thereby, a shank formed integral with the head and passable through said bore for engagement with the nut, said handle having a groove formed in 90 its end, said head having a convexed edge for engaging said groove to prevent rotation of the head upon manipulation of the nut.

In testimony whereof, I affix my signature in the presence of two witnesses.

HERMAN W. UHLENKOTT.
